CLAIM

The ornamental design for a dual probe sensor, as shown and described.

DESCRIPTION

FIG. 1 is a front-top-left isometric view of a dual probe sensor of the design;

FIG. 2 is a back-bottom-right isometric view of the dual probe sensor of FIG. 1;

FIG. 3 is a front view of the dual probe sensor of FIG. 1; FIG. 4 is a back view of the dual probe sensor of FIG. 1; FIG. 5 is a right side view of the dual probe sensor of FIG. 1;

FIG. 6 is a left side view of the dual probe sensor of FIG. 1; FIG. 7 is a top view of the dual probe sensor of FIG. 1; and, FIG. 8 is a bottom view thereof is a bottom view of the dual probe sensor of FIG. 1.

It is understood that the broken lines in the drawing figures are for illustrative purposes only and form no part of the claimed design.
